PAPER WINDING MACHINE

Everett W. Clem, Shrewsbury, and John P. Muntion, Worcester, Mass., assignors to Rice Barton Corporation, Worcester, Mass., a corporation of Massachusetts

Application November 15, 1946, Serial No. 709,954

6 Claims. (Cl. 242—65)

1

This invention relates to paper winding machines and more particularly to that type of paper winding machine known as a "Pope Reel" winding machine.

The "Pope Reel" type of machine is used principally for winding a web of paper produced by a paper-making machine onto a winding roll. With this type of machine the end portion of a paper web is wound on an empty winding spool or roll which is supported, in a position herein termed its initial position, in such a manner that the roll engages the under driving drum to the end that the latter element will drive the winding roll. The end portion of the web will begin to wind on said roll and as soon as the web has become firmly fixed to the roll by the winding action the roll is moved into a secondary position where it remains until the roll has become filled, such movement into this secondary position enabling an empty winding roll to be brought into the primary or initial position.

As soon as the roll which is in the secondary position has become filled, the web is severed and automatically transferred to the new empty winding roll, thus to permit the filled winding roll to be removed without stopping the winding of the paper web.

The usual "Pope Reel" machine, as well as the present device, utilizes two separate supporting frames which are movable with respect to each other thereby to admit of transference of a roll from one to the other frame, from the initial to the secondary or running position.

However, it has been found that the above described "Pope Reel" mechanism has a serious fault in that the paper web may be mutilated whenever an empty winding roll in its initial position is lowered toward the driving drum for the purpose of engaging the paper web which is being wound upon another roll disposed in the secondary position. This damage occurs for the reason that the empty winding roll, prior to its engagement with the moving paper web, is not rotating and, therefore, the relatively weak paper web is damaged as the same is pressed between the rotating driving drum and the non-rotating winding roll. In other words, the empty winding roll depends upon the friction existing between itself and the paper web to bring the stationary roll up to speed and as the paper web is relatively weak it often cannot withstand this treatment and it is, as a consequence, damaged.

It is, therefore, a primary object of the present invention to provide a paper winding machine with means whereby the empty winding roll may

2

be rotated and brought up to an appropriate angular velocity preparatory to lowering the same against a moving paper web.

It is a further object of the present invention to provide such a winding roll accelerating means which may be so constructed and arranged that it will not interfere with the normal operation of a "Pope Reel" paper winding machine.

With the above and other objects in view as will hereinafter appear, the invention comprises the devices, combinations and arrangement of parts hereinafter set forth and illustrated in the accompanying drawings of a preferred embodiment of the invention from which the several features of the invention and the advantages attained thereby will be readily understood by those skilled in the art.

In the accompanying drawings:

Fig. 1 represents a side elevation view of a paper winding machine to which the present invention is applied.

Fig. 2 represents a front elevation of the paper winding machine taken substantially along line 2—2 of Fig. 1 and showing the present invention as applied thereto.

Fig. 3 represents an enlarged sectional view taken substantially along line 3—3 of Fig. 2.

Fig. 4 represents an enlarged top plan view of a portion of the present invention as shown in Fig. 2.

Fig. 5 is a sectional view taken substantially along line 5—5 of Fig. 4.

Fig. 6 is a sectional view taken substantially along line 6—6 of Fig. 4.

Fig. 7 is a diagrammatic drawing representing the air system for the present machine.

Fig. 8 represents a top plan view of the right hand portion of the machine as disclosed in Fig. 2.

Referring particularly to Figs. 1, 2 and 8, the present invention is incorporated in a winding machine which comprises the side frame members 10 and 11 between which is mounted a driving shaft 12 carrying the usual driving drum 13 and having its distal end mounted in a bearing block 12'. This driving drum 13 may be driven by a motor 14 or other suitable driving means connected with the shaft 12. Mounted adjacent each end of the driving drum 13 and coaxially of and about the shaft 12 is one of a pair of quadrant arms 15 and 16. The top portion of each of these quadrant arms 15, 16 is provided with a yoke 19 which is adapted slidably to receive a journal box 20, only one of which is shown herein. Each journal box 20 has rotatably mounted therein one end of a shaft 21 upon which is

mounted the usual paper winding roll 22. As is usual with this type of mechanism, the journal boxes 20 are adapted for vertical movement within the yokes 19, 18 to the end that the paper roll 22 may be readily inserted therein.

Referring particularly to Fig. 1, the lower end portion 23 of the quadrant arm 15 has pivotally secured thereto one end of a link member 24 the other end of which is pivotally mounted upon a depending crank 25 which in turn is pivotally carried upon a stub shaft 26 carried by the frame member 10. Also pivotally secured upon the crank 25 is one end of a piston 27 the other end of which is slidably received within a hydraulic cylinder 28 whose rear portion is pivotally carried upon a pin 29 fixed upon the frame member 10. This mechanism forms no part of the present invention and it will suffice to state that the quadrant arm 15 is similarly provided with such mechanism. Also, it is only necessary to state that the cylinder 28, associated with the arm 15, and a similar cylinder (not herein shown), associated with the arm 16, are adapted to be connected with a hydraulic system to the end that a single hand-actuated valve will control the movements of the pistons contained within the cylinders. It is to be understood that as the piston 27 is forced in and out of the cylinder 28 the crank 25 will be swung about its pivot 26 so that the arm 15 will move in clockwise and counterclockwise directions about the shaft 12. The arm 16, having a similar hydraulic actuating mechanism which is connected along with the mechanism of arm 15 to a common hydraulic system, will be actuated in synchronism with arm 15. Thus, an operator by manipulating a single hydraulic valve (not herein shown) may readily swing the quadrant arms 15 and 16 about the shaft 12 thereby to swing the roll 22 about the driving drum 13. Figs. 1 and 2 illustrate the quadrant arms in their initial positions.

Also journaled in the opposite frame members 10 and 11 is a shaft 29 upon which are rigidly mounted a pair of similar arms of which only one, bearing the number 30 is herein shown. This arm 30 is provided with a yoke 31 of a design substantially similar to that of yoke 19. It is the function of the arm 30, and its associated arm not herein shown, to receive the paper winding roll whenever the quadrant arms 15 and 16 are swung in a clockwise direction thus to transfer the journal boxes 20 of the winding roll 22 into the yokes of arm 30 and its associated arm.

A depending portion 32 of the arm 30 has pivotally connected therewith one end of a piston 33 which has its other end portion slidably received within a hydraulic cylinder 34. This hydraulic cylinder is pivotally secured upon a pin 35 which in turn is carried by the frame 10. The present machine is adapted to have the arm which is associated with arm 30 provided with a similar hydraulic cylinder and piston arrangement so that both of the arms may be moved in synchronism by means of a hydraulic valve which is not herein shown. It is to be understood that as the piston 33 slides into and out of the cylinder 34 the arm 30 is forced to rotate in clockwise and counterclockwise directions respectively.

In the use of the above described mechanism a web of paper 36 is delivered from the driers, calenders, or other parts of a paper making machine, none of which is herein shown, thus, to be wound around the winding roll 22 that is journaled loosely and removably in the upper ends of the quadrant arms 15 and 16. The peripheral

contact between the driving drum 13 and the winding roll 22 is such as to drive the roll 22 in a counterclockwise direction (referring to Fig. 1) thereby to wind the web or paper sheet upon the roll 22 which is held in engagement with the drum 13 during the winding process by its weight. After a predetermined amount of paper is accumulated on the roll 22, the quadrant arms 15 and 16 may be swung in a clockwise direction (referring to Fig. 1) thereby to transfer the roll 22 from its initial position as shown in Fig. 1, to a secondary position within the arm 30, all in the usual manner. The roll 22 in this secondary position continues to accumulate paper until it is filled at which time the paper web is severed from the filled roll and quickly transferred to an empty roll which has been placed within the arms 15 and 16. This empty roll is held out of contact with the paper web until just prior to the time the web is to be severed from the filled roll and at that time the empty roll is lowered upon the web which is thereafter severed and then quickly wound thereabout.

In order to retain the empty winding roll out of engagement with the paper web until the web is severed from the filled roll, the present machine is provided with a pair of upstanding arms 31, 37 each of which is rigidly secured upon the inner end portion of a respective one of the stationary bearing blocks 38, 38. The top portion of each of the arms 31, 37 is formed as an inclined plane or cam surface 39 (see Fig. 1) and when the quadrant arms 15 and 16 are in the position shown in Fig. 1 the winding roll 22 will rest upon the inclined plane or cam portions 39, 39 to the end that it will be held above and out of engagement with the paper web 36. Whenever it is desired to lower the winding roll against the web it is only necessary to turn the quadrant arms 15 and 16 in a clockwise direction until the roll is no longer in engagement with the arms 31, 37.

In order to initiate the rotation of the empty roll before the same is lowered into engagement with the web, the present winding roll shaft 21 is provided with a member 40 which extends from and coaxially of one end of the shaft. Upon the end of member 40 is rigidly secured a cup-like female clutch element which comprises a hub 41 from which extends a circular wall 42 having an annular flange 43 extending from the periphery thereof.

The present invention contemplates the use of a rotary male clutch element which may be inserted within this cup-like element for the purpose of initiating the rotation of the winding roll and bringing the latter element up to its proper speed at which time the rotary element may be removed from the cup-like element and the winding roll may be lowered against the paper web. In its preferred form this rotary or driving element takes the form of an air clutch designated generally by the numeral 44 and comprising a hollow hub portion 45 which is keyed or otherwise secured upon an endwise shiftable shaft 46. Bonded upon the periphery of the hub 45 as at 47 is an annular rubber tire 48 having an annular hollow chamber 49 formed therein, which chamber is in direct communication with one end of a radial bore 50 formed within the hub 45. The inner end of the bore 50 opens directly upon an annular groove 51 formed about the periphery of the shaft 46 which has a radial bore 52 disposed therein with the outer end portion of this bore in communication with the annular groove 51. The inner portion of the bore 52 leads to a

longitudinal bore 53 formed within the shaft 46. Thus, if fluid under pressure is supplied to the shaft bore 53, the chamber 49 will be expanded thereby to increase the radius of the tire periphery. The diameter of the tire 48 is such that it is slightly less than the inner diameter of the flange 43. Therefore, the tire 48, when deflated, may be readily inserted into the flange 43 and then it may be inflated to the end that the periphery of the tire may engage the flange for the purpose of driving the same.

Referring particularly to Figs. 2 and 4, the shaft 46 is slidably received within a longitudinal bore 54 formed within a driving shaft 55 which is rotatably journaled in any suitable manner within spaced pillow blocks 56 and 57 which are rigidly mounted upon a table top 58. The rear end portion of the driving shaft extends slightly beyond the block 57 and has secured thereto a pulley 59 which is belted to a driving means hereinafter described.

Formed intermediate the ends of the driving shaft 55 is a slot 60 in which is disposed a key 61 the inner portion of which is disposed within a longitudinal groove 62 formed within the shaft 46. A collar 63 is received over the driving shaft 55 and is secured thereupon by means of a set screw 64 for the purpose of locking the same in place over the key 61. This construction permits the shaft 46 to be moved back and forth within the driving shaft 55 but at the same time it prevents the shaft 46 from turning relative to the driving shaft 55. Therefore, rotation of the driving shaft 55 will drive the male clutch member 44 in synchronism therewith.

The rear end portion of the shaft 46 extends beyond the confines of the driving shaft 55 and it has secured to its end a suitable fluid coupling 65 which has a fluid-delivering hose 66 connected therewith. This coupling 65 is adapted to deliver air under pressure to the shaft bore 53 and at the same time permits relative movement between the shaft 46 and the hose 66.

Depending from the table top 58 are table legs 67 for supporting the same and these legs straddle an extended portion of the driving drum shaft 12 which has a belt pulley 68 secured thereto. The motor 14 having a shaft 69 extending therefrom is connected to the pulley 68 by means of a belt 70 and pulley 71 which is carried by the shaft 69. Rotation of the motor will, therefore, drive the driving drum 13. A second pulley 72, fast upon the shaft 69, is connected by means of a belt 73 to the pulley 59 and, therefore, the motor 14 is also effective for driving the male clutch member 44. Bearing blocks 12' and 69' are provided for properly supporting the shafts 12 and 69 respectively.

Mounted upon a table cross-piece 74 is an idler pulley 75 which engages the belt 73 and functions as a belt tightener.

Referring particularly to Figs. 2, 4, and 5 the shaft 46 is provided with means whereby an operator may, at will, slide the shaft back and forth within the bore 54. In its preferred form this means comprises a ball bearing unit 76 with its inner race made fast to the shaft 46 and its outer race having a collar 77 force-fitted over it. The collar 77 has a pair of bosses 78, 78 disposed on opposite sides thereof for the purpose of receiving a pair of yokes 79, 79 which are carried upon the end of a shipper element 80. The lower end portion of the shipper element 80 is pivotally carried upon a pin 81 which is mounted within a flange 82 secured upon a leg 67 of the table unit.

Intermediate its ends the shipper element 80 is pivotally connected with a piston rod 83 which is slidably received within an air cylinder 84 bolted to the table as at 85. It is to be understood that as the piston 83 is forced back and forth within the air cylinder 84, the shipper element 80 becomes effective to extend the clutch 44 into and to retract the clutch out of the flange 43 of the female clutch member.

Referring particularly to Fig. 7, a pair of air-conducting hoses 86 and 86' may be connected to the respective ends of the cylinder 84 for the conducting air under pressure to each side of a piston head 87 which is carried by the piston 83. The hoses or conduits 86 and 86' are both connected to a selector valve 88 which in turn is connected with a source of fluid pressure 89. Therefore, an operator may, by merely operating the valve 88, shift the clutch 44 back and forth relative to the female clutch member. To facilitate the actual engagement of the clutch 44 and flange 43, the present mechanism is provided with a valve 90 which is connected to the fluid-coupling 65 and also to the source of fluid under pressure 89. Manipulation of valve 90 will be effective to inflate and deflate the clutch 44. Therefore, whenever it is desired to initiate the rotation of the winding roll 22 before engaging the same with the paper web, it is merely necessary to shift the clutch 44 to a position within the flange 43 and then inflate the clutch. The inflated clutch will engage the inner periphery of the flange 43 and as the clutch is rotated constantly by the motor, it will be effective to impart rotation to the winding roll 22. After the winding roll has been brought up to speed, the clutch may then be deflated and removed from the flange 43, after which the quadrant arms 15 and 16 may be rotated slightly in a clockwise direction thereby to slide the winding roll off the inclined planes 39, 39 and downwardly towards the driving drum and against the paper web.

It is to be understood, of course, that the present mechanism is so designed that whenever the winding roll 22 is in its initial position and out of contact with the paper web, the male clutch element is disposed coaxially of the female clutch element which is carried by the winding roll.

From the above description it is clear that the present clutching means in no way interferes with the normal operation of the paper winding mechanism and furthermore, it comprises a most efficient means whereby the winding roll may be brought up to speed preparatory to bringing the same into engagement with the paper web.

We claim:

1. A paper winding machine comprising, a driving drum, means for rotating said driving drum, a paper winding roll normally disposed in surface contact with said driving drum so as to be driven thereby, means initially for supporting said winding roll out of contact with said driving drum, a clutch element extending coaxially of and from one end of said winding roll, a second clutch element disposed coaxially of said first mentioned clutch element whenever said winding roll is supported in said initial position, means for rotating said second clutch element, means for shifting said second clutch element into and out of engagement with said first clutch element thereby to impart rotation to said winding roll while the same is out of contact with said driving drum, and means for bringing said rotating winding roll into operative engagement with said driving drum.

2. A paper winding machine comprising, a driving drum, means for rotating said driving drum, a paper winding roll normally disposed in surface contact with said driving drum so as to be driven thereby, means initially for supporting said winding roll out of contact with said driving drum, a female clutch element extending coaxially of and from one end of said winding roll, a male clutch element disposed coaxially of said female clutch element whenever said winding roll is supported in said initial position, means for rotating said male clutch element, fluid actuated means for shifting said male clutch element into and out of engagement with said female clutch element thereby to impart rotation to said winding roll, and means for shifting said winding roll into operative engagement with said driving drum.

3. A paper winding machine comprising, a driving drum, means for rotating said driving drum, a paper winding roll normally disposed in surface contact with said driving drum so as to be driven thereby, means initially for supporting said winding roll out of contact with said driving drum, a female clutch element extending coaxially of and from one end of said winding roll, an expandable male clutch element disposed coaxially of said female clutch element whenever said winding roll is supported in its initial position, means for rotating said male clutch element, means for shifting said male clutch member into and out of making relation with said female clutch element, fluid actuated means for expanding said male clutch member into engagement with said female clutch element thereby to impart rotation to said winding roll, and means for shifting said winding roll into operative engagement with said driving drum.

4. A paper winding machine comprising, a driving drum, means to rotate said driving drum, a pair of quadrant arms each pivotally supported adjacent a respective one of the end portions of said driving drum, a paper winding roll carried by said quadrant arms and normally disposed in surface contact with said driving drum so as to be driven thereby, a stationary arm having an inclined cam surface disposed adjacent each end portion of said driving drum for initially supporting upon such cam surfaces, in cooperation with said quadrant arms, said winding roll directly above and out of contact with said driving drum, an auxiliary winding roll driving means operatively connected with said first mentioned means, means for connecting and disconnecting said auxiliary driving means to and from said winding roll while the latter is out of contact with said driving drum thereby initially to rotate the same, and means for shifting said quadrant arms about said driving drum and relative to said inclined cam surfaces so as to lower said winding roll into surface engagement with said driving drum.

5. A paper winding machine comprising, a driv-

ing drum, means to rotate said driving drum, a pair of quadrant arms each pivotally supported adjacent a respective one of the end portions of said driving drum, a paper winding roll carried by said quadrant arms and normally disposed in surface contact with said driving drum so as to be driven thereby, means disposed adjacent each end portion of said driving drum for initially supporting, in cooperation with said quadrant arms, said winding roll directly above and out of contact with said driving drum, means extending coaxially of and from one end of said winding roll, an auxiliary driving device normally disposed in a position remote from said winding roll, means for shifting said auxiliary driving device into and out of engagement with said last mentioned means for imparting rotation to said winding roll while the same is disposed above and out of contact with said driving drum, and means for shifting said winding roll into surface engagement with said driving drum.

6. A paper winding machine comprising, a driving drum, means to rotate said driving drum, a pair of quadrant arms each pivotally supported adjacent a respective one of the end portions of said driving drum, a paper winding roll carried by said quadrant arms and normally disposed in surface contact with said driving drum so as to be driven thereby, a stationary arm having an inclined cam surface disposed adjacent each end portion of said driving drum for initially supporting upon such cam surfaces, in cooperation with said quadrant arms, said winding roll directly above and out of contact with said driving drum, clutch means extending coaxially of and from one end of said winding roll, an auxiliary driving device normally disposed in a position remote from said winding roll, means for shifting said auxiliary driving device into and out of engagement with said clutch for imparting rotation to said winding roll while the same is disposed above and out of contact with said driving drum, and means for shifting said quadrant arms about said driving drum and relative to said inclined cam surfaces so as to lower said winding roll into surface engagement with said driving drum.
